CLAIM

The ornamental design for a eight-seat game machine, as shown and described.

DESCRIPTION

FIG. 1 is a perspective view of a eight-seat game machine showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is an enlarged view of the area labeled 8 in FIG. 1; and,

FIG. 9 is an enlarged view of the area labeled 9 in FIG. 6. The dash-dash broken line showing in the figures are for the purpose of illustrating portions of the eight-seat game machine which form no part of the claimed design. The dash-dot-dash broken lines depict boundaries and form no part of the claimed design. The dash-dot-dot-dash broken lines surrounding portions of the eight-seat game machine in FIGS. 1 and 6 and illustrated in enlarged views in FIGS. 8 and 9 form no part of the claimed design.
